The ornamental design for a septal splint, as shown and described.

DESCRIPTION

FIG. 1 is a front perspective view of the first embodiment of a septal splint showing my new design;

FIG. 2 is a side elevational view thereof;

FIG. 3 is a side elevational view of the opposite side from that shown in FIG. 2;

FIG. 4 is a front elevational view thereof;

FIG. 5 is a rear elevational view thereof;

FIG. 6 is a top plan view thereof; and,

FIG. 7 is a front perspective view of a second embodiment of a septal splint, all other sides being opposite as in FIGS. 1-6 of the first embodiment.
